UNITED STATES PATENT OFFICE.

ALBERT GYLFE AND ISRAEL OLSON, OF BERWYN, ILLINOIS.

THERMOSTATIC ALARM.

No. 839,066.

Specification of Letters Patent.

Patented Dec. 18, 1906.

Application filed July 11, 1904. Serial No. 216,155.

To all whom it may concern:

Be it known that we, ALBERT GYLFE and ISRAEL OLSON, citizens of the United States, residing at Berwyn, in the county of Cook 5 and State of Illinois, have invented a new and useful Thermostatic Alarm, of which the following is a specification:

Our invention relates to a device comprising a trip-lever which is released at a predetermined temperature; and the objects of our improvement are, first, to provide a device which is extremely sensitive to the changes in temperature; second, to afford facilities for adjustment to release the trip-lever at any 15 desired temperature; third, to make a cheap, simple, and durable device, and other objects, which will become apparent from the description to follow.

This invention consists of one or more hollow disks or diaphragms containing a fluid arranged in a frame so as to control a pivoted arm against which the trip-lever rests.

The device illustrated and to be described shows one form of construction, and it is obvious 25 that the construction may differ radically from that shown and still embody our invention.

Referring to the drawings, Figure 1 is a side elevation of a device embodying our invention. Fig. 2 is a plan view of the same. Fig. 3 is a front elevation of the same, and Fig. 4 is a section on line 4-4 of Fig. 2.

Similar reference characters refer to similar parts throughout the several views.

The base 5, upright 6, and top 7 constitute the frame of the machine. The base 5 and top 7 are provided with the concentric perforations 8 and 9, respectively. The perforation 8 is provided with a screw-thread into 35 which is fitted the screw 10. The top end of the screw 10 is secured to the lower side of the hollow disk 11, which is hermetically sealed and contains a liquid 12, preferably alcohol. The two walls of the disk 11, including 40 the alcohol, are preferably made of very thin material and are exposed as much as possible to the surrounding atmosphere, so that the temperature of the atmosphere is readily transferred to the alcohol. To increase 45 the rigidity of the disk 11 without thickening the walls, the ribs 13 are provided. We have shown two disks 11 in the drawings, but one or more may be used, whichever is found most practical. To the top side of the upper disk 11 is secured a push-pin 14, fitting loosely in the perforation 9 in the top 7.

When the temperature of the alcohol is raised, it will expand and bulge out the sides of the disks 11, thus increasing the distance from the bottom side of the lower disk 11 to the top side of the upper disk 11, the opposing walls of the separate disks being connected by rigid fastenings, as the tubes 15. The lower support of the disks—i. e., the screw 10—being held from longitudinal movement in the base 5, it is evident that the pin 14 must slide in the perforation 9 as the temperature of the alcohol 12 increases or decreases. The pin 14 extends above the top 7, where it contacts with the under side of an arm 16, pivoted to the top 7 at 17, and its free end guided between two vertical lugs 18 on the top 7. The point of contact between the pin 14 and arm 16 is preferably nearer the pivot than the free end of said arm, and a spring 19 is provided to constantly hold the arm 16 down against the pin 14.

Loosely pivoted on a pin 20, secured to a lug 21 on the base 5, is a weighted trip-lever 22, normally resting in an oblique position with its free end against the free end of the arm 16. The pivotal axis of the lever 22 and arm 16 are at right angles to each other, and the parts are so arranged that the trip-lever 22 is allowed to drop by gravity or otherwise when the arm 16 is moved up against the tension of the spring 19. The amount of movement necessary by the arm 16 to release the trip-lever 22 depends on the extent of the lap of the free end of said lever over the free end of the arm 16—i. e., if the lap is slight the movement required is slight, and vice versa. The trip-lever 22 when released is arranged to contact with the releasing-lever of any desired alarm, as an alarm-bell, (not shown,) or it may serve to close a switch for an electric bell. Assuming that the dropping of the lever 22 will cause an alarm-bell to ring and the device is placed in a room, when the temperature of the room rises sufficiently the alcohol 12 will become heated, expand, and cause the arm 16 to be moved upward by the pin 14, the lever 22 will drop and cause the bell to ring.

To facilitate adjusting the disks 11, so as to release the trip-lever 22 at any desired temperature, we provide means to adjust the screw 10 longitudinally in the perforation 8. The screw 10 is rigidly secured to the disks 11, and to adjust the screw the disks are turned in the proper direction. To enable the ready adjustment to the desired temper-

ature, the upper face of the upper disk 11 is provided with a graduated scale 23, having the degrees marked thereon. The upright 6 may conveniently serve as the indicating-point.

In Fig. 2 of the drawings the sixty-degree mark is placed nearest the upright 6, indicating that the alarm will be sounded when the temperature in the room reaches sixty degrees or more.

A stop-pin 24 may be provided on the disk 11 to contact with the upright 6 and prevent accidentally turning the disk in the wrong direction.

Having thus fully described our invention, what we claim as new, and desire to secure by Letters Patent of the United States, is—

1. In a device of the class described, a U-shaped frame provided with concentric perforations in its extremities, a diaphragm containing liquid, a trip-lever, a pin rigidly secured to said diaphragm extending into one of said perforations, a second pin rigidly secured to said diaphragm extending into the other of said perforations, and means whereby said trip-lever is released by the expansion of said diaphragm.

2. In a device of the class described, a U-shaped frame having a perforation in one end and a screw-threaded hole in the other end concentric therewith, a diaphragm, a trip-lever, a pin rigidly secured to said diaphragm, extending through said perforation, a screw rigidly secured to said diaphragm co-operating with said screw-threaded hole and means whereby said trip-lever is released by the expansion of said diaphragm, comprising a spring-pressed pivoted lever in contact with said pin.

3. In a device of the class described, a vertical frame having two horizontal arms, one arm provided with a perforation and the other arm provided with a screw-threaded hole concentric with said perforation, a trip-

lever, a plurality of diaphragms having their axis concentric with said perforation and said hole, a plurality of supports secured to the opposing sides of said diaphragms, a pin rigidly secured to the exposed side of one end diaphragm extending through said perforation, a screw secured to the exposed side of the other end diaphragm co-operating with said screw-threaded hole, one of said diaphragms having its peripheral edge graduated to indicate the adjustment of said pin, and means whereby said trip-lever is released by the expansion of said diaphragms.

4. In a device of the class described, a suitable frame, a diaphragm containing liquid having one side secured against movement to said frame, a pin arranged to slide in said frame secured to the other side of said diaphragm, a pivoted lever in constant contact with said pin and a second pivoted and weighted lever normally in contact with said first-named lever, so that the expansion of said diaphragm will permit said second-named lever to move to its operated position.

5. In a device of the class described, a suitable frame, a diaphragm containing liquid having one side secured against movement to said frame, said frame provided with a perforation, a concentrically-extending pin secured to the other side of said diaphragm arranged to move through said perforation and a pivoted trip-lever in constant contact with said pin whereby said trip-lever is moved when said diaphragm expands.

In testimony whereof we have signed our names to this specification, in the presence of two subscribing witnesses, this 7th day of July, 1904, at Chicago, Illinois.

ALBERT GYLFE.
ISRAEL OLSON.
